ELECTRON DISCHARGE DEVICE

Charles T. Goddard, New York, N. Y., assignor to
 Western Electric Company, Incorporated, New
 York, N. Y., a corporation of New York

Application August 4, 1942, Serial No. 453,515

5 Claims. (Cl. 250—27.5)

1

This invention relates to electron discharge devices, and more particularly to devices of the types used in ultra high frequency transmission systems.

In such devices the efficiency thereof depends greatly upon the manner of control of the electrons from the filament to the anode and under the function of the grid. At certain intervals during the functioning of such devices, the grid structure may attract certain of the electrons and if this attraction may be reduced to a minimum, the efficiency of the device will be greatly increased. Grid current resulting from attraction of the electrons toward the grid is commonly known as grid loading.

An object of the invention is to provide an electron discharge device, particularly one where the grid loading is reduced to a minimum.

With this and other objects in view, the invention comprises an electron discharge device including a filament, anode and control grid, the latter being constructed in a manner such that portions of the grid which do not actively contribute to power output are prevented from absorbing power from the electron stream.

Other objects and advantages will be apparent from the following detailed description when considered in conjunction with the accompanying drawing, wherein

Fig. 1 is a side elevational view of the device, portions thereof being broken away;

Fig. 2 is a fragmentary perspective view of the elements of the device;

Fig. 3 is a fragmentary top plan view of the grid and filament, and

Figs. 4 and 5 are sectional views of other species of grid structures.

Referring now to the drawing, the device includes a transparent vessel 10 in which leads 11 are positioned for the mounting of filament supports 14 and 15, a grid 16 and an anode 17 thereon.

The grid 16 is of the fin type shown in Figs. 1 and 2, consisting of a mandrel 18 about which convolutions of a grid wire 19 are wound, leaving loop portions projecting in front of the mandrel as shown in Fig. 2. In the present instance the mandrel is formed of solid nickel and is supported, together with the convolutions, by a bracket 20 adapted for mounting upon its respective lead 11. The supports 14 and 15 have a filament 22 positioned therebetween, the ends of the filament being secured to the supports by suitable means such as welding. The anode 17 has a central portion 24 similar in contour to the free portions of the grid convolutions 19, yet spaced equal distances therefrom throughout the area of this portion of the anode.

It is known that during the functioning of such devices, a positive potential is applied to the anode 17, the filament 22 being negative, while

2

the potential of the grid is for the major portion negative with respect to the filament. Yet positive peaks in grid potential intermittently occur which cause attraction of the electrons and result in a current flow in the grid circuit. This attraction would occur, of course, only in the electron paths where the grid wire is disposed, if it were not for the mandrel 18, which is a part of the grid assembly. A flat surface 26 of the mandrel is thus positioned where it would attract electrons during the intervals when the grid is made positive, this surface providing a greater area than those in which the grid convolutions are disposed and providing a large attracting surface for the electrons during these intervals. The attraction for this surface may be eliminated, however, by covering the surface with a suitable material. In Fig. 2 an insulating material 27 is disposed on the surface 26 and may, if desired, be extended over the ends of the bracket 20. This material may be disposed on these grid portions by spraying or in sheet form, and otherwise secured in place.

As another illustration, attention is directed to Fig. 4, where the same reference numerals are applied to the mandrel and the associated parts, the surface 26 in this instance, however, being provided with another material such as aluminum oxide indicated at 29, this material being sprayed upon the surface of the mandrel.

In Fig. 5, another cross-sectional view of the mandrel 18 with the associated parts therein bearing the same reference numerals as in Fig. 2, illustrates another species wherein a cover plate 30 of a suitable material such as nickel, with one surface coated as at 31 with an insulating material, is secured to the surface 26 of the mandrel by suitable means such as welding.

It will thus be apparent that by covering the surface 26 of the mandrel with a material or materials which will not permit the passage of electrons at the positive intervals, the grid loading, that is, the flow of electronic current in the grid circuit, will be greatly reduced. This is of utmost importance in maintaining the device at its maximum efficiency.

The structure previously described embodies but one, yet a very important, feature in maintaining the maximum efficiency of the device. Another part of the same problem lies in the additional grid loading introduced by portions of the grid which extend beyond the ends of the anode. In current practice, the grid in a structure of the type considered here is usually extended beyond the ends of the anode in order to prevent the direct flow of electrons to the anode from portions of the filament extending beyond the ends of the anode. However, this expedient results in increased grid loading because of the distorted nature of the electric field in this region,

All portions of the anode being relatively remote from this portion of the grid and filament, the great majority of electric field lines of force from the filament must terminate on the grid wires instead of passing between the grid wires as they do in the region bounded by the ends of the anode. This results in additional grid current or loading. Therefore, it would be advantageous to find some means of using a shorter grid to reduce the grid loading without permitting a direct flow of electrons to the anode from portions of the filament extending beyond the ends of the anode. This is accomplished through the aid of shields 34 of the contour illustrated in Figs. 1 and 3, and mounted upon the bracket 20 above and below the grid.

As will be observed, the shields are of general flat structure cut away at 35 to conform to the contour of the grid, the cutaway portion being substantially of the dimensions of the grid and smaller than that of the portion 24 of the anode. End portions 36 of the shields are bent to conform to the grid or to the portion of the bracket adjacent the mandrel 18 and are secured thereto by suitable means such as welding.

With the shields 34 in place, it will be apparent that they will intercept any path which electrons may take in attempting to pass from the filament portion beyond the grid to the anode. Although the covers 27, 29 and 30-31 perform their individual functions which may be separate from the functions performed by the shields 34, it is known that they all form a part of the grid structure and their functions overlap in accomplishing a unitary result, namely, the reduction of grid current or loading without detracting from the control features of the grid.

Although specific improvements of the invention have been shown and described, it will be understood that they are but illustrative and that various modifications may be made therein without departing from the scope and spirit of this invention as defined by the appended claims.

What is claimed is:

1. An electron discharge device comprising an elongate electron emitting filament, a control grid having a mandrel, with a flat inner face, mounted parallel with the filament and formed of a conductive material to attract electrons emitted by the filament, and a grid wire wound about the mandrel and supported thereby with free loops in the convolutions of the wire extending about the filament, an anode partially surrounding the grid loops and the filament, and a member disposed on the flat inner face of the mandrel to shield the mandrel against the attraction of the electrons.

2. An electron discharge device comprising an elongate electron emitting filament, a control grid having a mandrel mounted parallel with the filament with its ends terminating short of the ends of the filament and formed of a conductive material to attract electrons emitted by the filament, and a grid wire wound about the mandrel and supported thereby with free loops in the convolutions of the wire extending about the filament, a support for the grid, an anode partially surrounding the grid loops and the filament, a member disposed on the inner face of the mandrel to shield the mandrel against the attraction of the electrons, and members mounted upon the support adjacent the ends of the mandrel and

extending about the filament at each end of the grid to shield the anode from electrons emitted from portions of the filament extending beyond the ends of the grid.

3. An electron discharge device comprising an elongate electron emitting filament, a control grid having a mandrel mounted parallel with the filament and formed of a conductive material to attract electrons emitted by the filament, and a grid wire wound about the mandrel and supported thereby with free loops in the convolutions of the wire extending about the filament, a support for the grid extending about the mandrel thereof excepting the inner face of the latter, an anode disposed adjacent the grid loops, and means disposed on the inner face of the mandrel to shield the mandrel against the attraction of the electrons.

4. An electron discharge device comprising an elongate electron emitting filament, a control grid having a mandrel mounted parallel with the filament and formed of a conductive material to attract electrons emitted by the filament, and a grid wire wound about the mandrel and supported thereby with free loops in the convolutions of the wire extending about the filament, a support for the grid extending about the mandrel thereof excepting the inner face of the latter, an anode disposed adjacent the grid loops, and a covering of insulating material disposed on the inner face of the mandrel to shield the mandrel against the attraction of the electrons.

5. An electron discharge device comprising an elongate electron emitting filament, a control grid having a mandrel mounted parallel with the filament and formed of a conductive material to attract electrons emitted by the filament, and a grid wire wound about the mandrel and supported thereby with free loops in the convolutions of the wire extending about the filament, a support for the grid extending about the mandrel thereof excepting the inner face of the latter, an anode disposed adjacent the grid loops, and a covering of aluminum oxide disposed on the inner face of the mandrel to shield the mandrel against the attraction of the electrons.
